UNITED STATES PATENT OFFICE

THOMAS W. LLEWELLYN AND JAMES J. DOYLE, OF SYRACUSE, NEW YORK, ASSIGNEES
TO HOWARD P. DENISON, OF SYRACUSE, NEW YORK.

COLLAR-MOLDING MACHINE.

1,208,710.

Specification of Letters Patent.

Patented Dec. 12, 1916.

Original application filed June 26, 1913, Serial No. 775,875. Divided and this application filed November 18, 1914. Serial No. 872,048.

To all whom it may concern:

Be it known that we, THOMAS W. LLEWELLYN, and JAMES J. DOYLE, citizens of the United States, and residents of Syracuse, in the county of Onondaga and State of New York, have invented a certain new and useful Collar-Molding Machine, of which the following is a specification.

This invention relates to collar molding machines of the type disclosed in our application, Sr. No. 775,875, filed June 26, 1913, of which this application is a division.

The invention has for its object a ring on which the collars are molded, which ring is provided in a particularly simple and efficient manner with yielding portions arranged to underlie the folds in the hems at the ends of the collar; and it consists in the novel features of construction hereinafter set forth and claimed.

In describing this invention, reference is had to the accompanying drawing in which like characters designate corresponding parts in all the views.

Figure 1 is a plan view of a ring and its support and contiguous parts, which ring embodies our invention. Fig. 2 is a sectional view on line A—A, Fig. 1. Fig. 3 is a plan view of the ring rolled flat.

1 designates the ring. 2 is the support or carrier therefor, in which it is set edgewise, the ring being held in the support by a retainer 3.

4 is a member carried by the hub 5 of the ring. This member serves to prevent the collar from leaving the ring and to strip the same from the heated head into which the ring with the collar thereon is moved to mold the collar, as will be understood by those skilled in the art. For the purpose of making this invention clear to one skilled in the art, it is thought that a description and illustration of the complete collar molding machine is unnecessary, and for a full description, reference is made to our application referred to.

The edge portions of the ring which underlie the folds in the hems at the ends of the collars are made yielding by weakening the marginal portions of the ring which are likely to underlie the folds in the hems in various sizes of collars. As here shown the ring is weakened by forming said portions with perforations preferably in the form of

slots 6 running parallel to the upper edge of the ring and near said edge, there being one slot 6 near one end of the ring and a plurality of slots 6 near the other end of the ring, the latter being placed so that one of them will underlie the fold in the hem at one end of the collar, while the single slot at the other end of the ring underlies the fold in the hem at the other end of the collar.

Usually the plurality of slots 6 are arranged in two rows, and those of one row are arranged staggered with those of the other, and the ends of the slots in one row extend beyond, or lap the ends of the slots of the other row, but are spaced apart therefrom, that is, the slots of one row do not open into the slots of the other row.

In order to facilitate the yielding of the slotted margin, each slot is formed with enlargements 7 at its ends.

In operation, the collar is placed on the ring with the hem at one end over the single slot and the hem at the other end overlying one of the plurality of slots at the other end of the ring, and when the molding operation takes place the folds in said hems, which are necessarily thicker than the remainder of the collar, will depress the underlying yieldable portions of the margin of the ring, and hence said folds will not be split or cracked.

What we claim is:

1. A ring for collar molding machines, the ring having edge portions depressible relatively to the body of the ring, substantially as and for the purpose described.

2. A ring for collar molding machines, the ring having portions of its upper margin weakened relatively to the body of the ring, substantially as and for the purpose specified.

3. A ring for collar molding machines, the ring having its margin formed with perforations, substantially as and for the purpose described.

4. A ring for collar molding machines, the ring having its margin formed with perforations extending along its upper edge, the perforations being arranged in two rows, one above the other, and those of one row being arranged staggered with those of the other row, substantially as and for the purpose specified.

5. A ring for collar molding machines, the

ring having its margin formed with perforations in the form of slots extending lengthwise of the margin of the ring, the slots being arranged in two parallel rows, one above the other, and the slots of one row being arranged staggered with those of the other row and the ends of the slots of one lapping the ends of the slots of the other and being spaced apart therefrom, substantially as and for the purpose set forth.

6. A ring for collar molding machines, the ring having its margin formed with perforations in the form of slots extending length-

wise of the margin of the ring, the ends of the slots being enlarged, substantially as and for the purpose described.

In testimony whereof, we have hereunto signed our names in the presence of two attesting witnesses, at Syracuse, in the county of Onondaga, in the State of New York, this 7th day of November, 1914.

THOMAS W. LLEWELLYN.
JAMES J. DOYLE.
